COLLAPSIBLE STAND FOR A FLEXIBLE
PROJECTION SCREEN
Herbert Riedel, Spitalmühlenstrasse 13,
Schwabisch-Hall, Germany
Filed May 11, 1961, Ser. No. 109,472
Claims priority, application Germany May 14, 1960
9 Claims. (Cl. 160—24)

Stands for projection screens that can be rolled up, 10 for home projection purposes for example, are well known, and so also are stands in collapsible form for transport. The present invention relates to a novel construction of such a stand, which is adapted on the one hand for production from synthetic material, and on the other hand ensures that the projection screen, in the operative condition, can be stretched to the desired extent. A further advance of this novel construction resides in the fact that a holding bar forming the main portion of the stand, mounted upon a preferably detachable base and carrying the members that hold the projection screen, 15 is made hollow so that it accommodates the projection screen in its interior.

The main feature of the stand according to the invention is a preferably vertically arranged holding bar, 20 mounted upon a detachable or collapsible base, there being mounted upon this holding bar two pairs of rocking arms which are designed for holding the two battens that keep the projection screen taut between them. At least one pair of these rocking arms are secured to a ring 25 slidable along the holding bar for the purpose of adjusting the desired tension of the projection screen. The slidable ring is in connection, by way of a screw-threaded bolt provided with a knurled disc, with a fixed ring provided on the holding bar. The upper pair of rocking arms are in particular linked to the upper holding ring that carries it in such a way that the rocking arms are rockable upwards out of their inoperative or transport position, in which they bear against the holding bar, 30 through about 120 to 150° towards the holding bar into the operative position, where they come into contact with abutments provided on this upper holding ring. The lower rocking arms are so linked to the lower holding ring that carries them that they are rockable upwards towards the holding bar through about 30 to 60° out of the transport position, in which they likewise bear against the holding bar, into the operative position, where they come 35 into contact with abutments provided on this lower holding ring.

The holding bar, as mentioned, is preferably made hollow, and consists in particular of a plurality of telescopically movable tubular sections, preferably two, which can be fixed relatively to one another in the drawn-out operative position by means of a knurled nut, constructed in a manner known per se, with for instance a conical thread.

The outer tube of the telescopic holding bar, or the rings holding the pairs of rocking arms, preferably the lower holding ring, may advantageously be so constructed that the parts of the detachable foot of the stand, in the transport condition, can be secured parallel to the holding bar, on its outer walls. In this case the lower holding ring is provided with slots which are arranged around its axis, and which correspond in number and form to the slidable foot members engaging, in the operative position, in a base on the inner holding tube. These slots in the lower holding ring, and also the foot members that are slidable into them in the transport condition, are slightly curved. The same curvature is exhibited by further slots, which are provided in a base on the lower (inner) tube member of the holding bar, and into which the foot members can be inserted for the operative con-

2

dition in such a way that three such foot members, for example, are spaced apart by angles of 120°.

The above and other objects, features and advantages of the present invention will become more readily apparent from the following description, reference being made to the accompanying drawing wherein:

FIG. 1 is a fragmentary front-elevational view of the stand for a projection screen according to the present invention;

FIG. 2 is a side-elevational view of the stand;

FIG. 3 is a transverse cross-sectional view showing the base of the stand in plan view;

FIG. 4 is a detail view of the central portion of the stand;

FIG. 5 is a detail view of the tightening and detent means;

FIG. 6 is a plan view of the lower carrier member of the stand;

FIG. 7 is a front-elevational view of the upper carrier member according to another embodiment of the invention;

FIG. 8 is a side-elevational view, parts broken away, of the post of a stand according to still another embodiment of the invention;

FIG. 9 is a front-elevational view of the stand of FIG. 8;

FIG. 10 is a plan view of the upper carrier member of the stand;

FIG. 11 is a plan view of the lower carrier member thereof;

FIG. 12 is a front-elevational view of the upper carrier member showing the detent means for securing its arms in their operative position;

FIG. 13 is an elevational view of one of the arms showing the detent means in greater detail;

FIG. 14 is a longitudinal cross-sectional view through the arm of FIG. 13;

FIGS. 15 and 16 are cross-sectional views illustrating the catch means of the arms of still another stand according to the invention;

FIG. 17 is an elevational view of a modified base; and

FIG. 18 is a transverse cross-sectional view through the base of FIG. 17 with the radially extending feet thereof removed.

FIG. 1 shows the general construction of the stand in the operative position, the transport position of the rocking arms being at the same time indicated in broken lines. The main portion of the stand is formed by a tubular post 1, extending vertically, the lower portion of which opens into a base, on which the foot members 27 are mounted. At the upper portion of this tube 1 is arranged an upper holding ring 2, which is axially slidable on the stand tube and is so connected, by way of a screw-threaded bolt 4 having a knurled disc 3, with a fixed ring 5 likewise provided on the stand tube that the distance between the rings 2 and 5 can be adjusted at the user's choice. On the movable ring 2 are mounted an upper pair of rocking arms 6 and 7. The ends of these rocking arms are capable of being connected with an upper batten 34, to which is secured one edge of the flexible projection screen, which is preferably capable of being rolled up. This projection screen is marked 17 in FIGS. 1 and 2.

As can be seen more particularly from FIG. 1, abutment surfaces 8 and 9 are provided on the upper holding ring 2 for the rocking arms 6 and 7; these abutment surfaces fix the operative position of the rocking arms when they are swung upwards about suitable pivots out of their position 6', 7', shown in broken lines, in which they lie against the outer tube 1 of the stand. In order that the rocking arms 6 and 7 may be fixed in their operative position, and may not fall back into their transport posi-

tion under the action of gravity, there are provided, on the holding ring 2, two pins 10 and 11 which can be resiliently pushed in, and which can be depressed by the user against a spring in the interior of the upper holding ring 2, as shown more particularly in FIG. 5, the rocking arms 6 and 7 slipping over the ends of the pins 10 and 11 until they clear the pins upon striking against the surfaces 8 and 9, whereupon these pins, being pressed outwardly again by their springs, secure the arms 6 and 7 in the operative position.

Further towards the middle of the tube 1 of the stand is provided a lower holding ring 24, which carries a lower pair of rocking arms 25, 26, constructed like the upper pair of rocking arms 6, 7. These two lower rocking arms also are swingable about suitable pivots on the lower holding ring 24, and bear, in the transport position, on the displacement into their tube 1. For operative position, they are swung upwardly through angles of about 30 to 60° in the manner illustrated, until they strike against abutments 35 and 36, which are provided on the holding ring 24. The ends of the rocking arms 25 and 26 are connectable with a second batten 37, which holds the lower edge of the projection screen 17.

For transport purposes the tube 1 can accommodate in its interior the rolled-up projection screen 17, with its battens 34 and 37. For this purpose the upper end of the tube 1 is provided with a resilient cover 20, which has on its periphery three resilient holding lugs 19 bearing on the external surface of the upper tube 1 of the stand; the lower ends of these lugs are slightly bent round towards the axis of the tube, so that in the corresponding position of the cover they can engage in holding slots 18. The lower bent edges of these holding lugs 19, or the edges of the holding slots 18, may advantageously be beveled in such a way that for the removal of the cover 20 mounted thereon only a slight rotation is necessary, during which the bent ends of the holding lugs 19 slip out of the slots 18, so that the cover can then be removed in an upward direction without hindrance.

The post 1 consists of two telescopically movable tubular members, an outer tube 21 and an inner tube 22. These two tubular members are connected with one another by a knurled nut 23, by the rotation of which, via a conical screw thread, the connection between the two tubes can be established or released.

For applying or removing a foot carrying the tubular post 1, there is provided on the tube member 22 a base 29, which is provided with holding slots 31 (FIGS. 3 and 4). Into the latter can be inserted three foot members 27, which are made slightly curved to correspond to the curvature of the slots 31. In order to fix the foot members 27 in the operative condition in the slots 31, the insertable ends of the foot members are each provided with one or more longitudinal slots 32 (FIG. 3), which result in a slight resilience of the outer foot-member ends formed thereby, thus enabling latching means 33 to be applied. The latter consist of lugs provided on the lateral edges of the slots, in which there fit corresponding cheeks on the resilient flanks of the foot members 27.

Each of the foot members 27 is provided on its upper side with one or more stiffening ribs 40 (FIG. 1), which, at their ends bearing on the base 29, are connected with one another by bridge pieces 41 (FIG. 3), the surfaces of which have the same curvature as the external surface of the base. By these bridge pieces 41 the foot members 27 are additionally braced against the base 29, owing to the fact that a sliding ring 42 which surrounds the base, and which is provided to lugs 43 corresponding with the number of foot members, can slide into an operative position with these lugs interposed between the stiffening ribs, so that the lugs 43 overlie in front of the bridge-pieces 41.

In order that the foot members 27 may require as little space as possible to accommodate them in the transport position of the stand, the following means are

provided: The lower holding ring 24, which holds the rocking arms 25, 26 and encircles the outer tube member 21 of the post 1 is recessed in a radial direction so as to present three slots 44 which conform to the slots 31 of the base 29. Into these slots 44 the foot members 27 taken out of the base 29 can be inserted in such a way that they bear against the external wall surface of the outer tube 21, as shown more particularly in FIG. 2, where these foot members, removed for transport, are designated with the numeral 27'. Owing to their own curvature they bear snugly upon the convex surface of the tube 22. In order that the ends of the foot members 27 directed in this position towards the upper holding ring 2 may be secured in their position for transport, a clamping ring 30 (FIG. 2) surrounding the tube 22 is provided. Ring 30 has resilient lugs 46 which bear upon the tube 22 in such a way that, after the clamping ring 30 has been slipped over the ends of the foot members 27, no further change of position can occur. The slots 44 of the holding ring 24 are moreover located, as is likewise shown in FIG. 6, on the side remote from the flattened portion of this holding ring, this flattened portion containing the fastening means for the rocking arms 25 and 26. Hence, in the transport position, the rocking arms 6 and 7 bearing against the tube 21, on the one hand, and the inserted foot members 27, on the other hand, do not get in one another's way. This is also to be gathered in particular from FIG. 2, which, as compared with FIG. 1, represents a rotation about the post 1 through 180°.

For holding the battens 34 and 37, which carry the flexible projection screen 17 by two opposite edges when it is stretched out in the operative condition, the following means are provided on the pairs of rocking arms 6, 7 and 25, 26, shown particularly in FIGS. 1, 2 and 5. Each rocking arm carries, in the neighborhood of its outer end, a pin 47, which is perpendicular to its plane of swing, and which fits into a corresponding bore or recess in the neighborhood of the ends of the battens 34 or 37. In the vicinity of this pin 47 there is also provided on the rocking arm a rivet or the like 48, around which a generally J-shaped clamping shackle 49 is rotatable whose bentover end yieldingly embraces the batten 34 or 37 in the operative condition, thereby securing it against slipping out of the pin 47. The clamping shackles 49 may be either fixed to the rivet or, as shown in FIG. 1, may be so constructed that they can be yieldingly slid into a slot in the latter, and can be correspondingly released.

When the projection screen 17 is stretched between the battens 34 and 37 in the manner described, the tension is in case of need increased to the desired degree by turning the knurled disc 3 (FIGS. 2 and 5) in the sense of an upward movement of the upper holding ring 2 away from the fixed ring 5. In the transport condition the clamping shackle 49 is turned through about 90° away from the projection surface (see the dotted position 49' in FIG. 1), so that the battens 34 and 37 can be removed and can be stored (after the rolling up of the projection screen 17), as indicated, in the interior of the tubes 21, 22.

FIG. 7 shows a simplified construction of the upper holding ring 2 for the rocking arms 6 and 7, wherein the spring-controlled abutment pin 10 or 11 of FIG. 5 can be dispensed with. The securing of these rocking arms 6 and 7 in the operative position is here effected by means of a two-armed shackle 50, rotatably supported at the pivot point 51, whose downwardly bent ends 52 and 53 of which are curved at their outer edges about approximately the thickness of the rocking arms 6 and 7, so that the shackles engage under these arms in the operative position and support them against dropping out. For the transport position, the slightly resilient shackle ends 52 and 53 are disengaged from the associated rocking arms, and the shackle 50 is brought preferably into

the position 50' shown in broken lines in FIG. 7. The rocking arms can then resume their positions shown in broken lines in FIG. 1, parallel to the tube 1.

Another embodiment is illustrated in FIGS. 8 to 14. This embodiment is distinguished from the first one by the fact that in the upper part of the tubular post 84 a telescopic tubular element 57 with an external screw thread 82 is slid over that post down to an abutment 81. This tubular element furthermore rests with an inwardly directed annular projection 83 upon the upper end of the tube 84. Owing to this, the tubular element 57 cannot slip down the post 84 during the tensioning operation of the screen. The annular projection 83 also serves for relieving any load on the collar 81.

The upper rocking-arm ring 55, with its internal screw thread 56 (FIG. 10), is screwed over the tubular element 57, the element 57 being rotated by means of a knurled projection 91. In order that the ring 55 may not turn with it, there is inserted from below, in a curved slot 88 in a segmental extension 87 of this ring, a correspondingly curved tongue 89, which is firmly clamped therein. The lower end of the tongue, slipping easily, engages in a slot 103 in a guiding ring 90, firmly secured to the post 84. The telescopic tubular element 57 is closed at the upper end by a cover 85, secured by means of a screw thread 86.

The upper rocking-arm ring 55 is provided, on the side opposite the segmental projection 87, with a double rocking-arm bearing 58, which comprises a front cover plate 60 and a rear cover plate 66 separated by a slot 59 into which the ends of the upper rocking arms are inserted, one from each side, and in which they are rotatably supported by bolts 67.

The rocking arms 68 are of shallow channel-shaped cross section, and are supplemented, in the neighborhood of the rocking bore 75 at one end, with a cover sheet 77 (FIG. 14) to form a box-like cross-section. In the vicinity of the rocking bore 75 an anti-friction roller 69 is journaled within slots 73. Through a central bore in the rocking arm there passes a guiding pin 71, which is supported within the rocking arm. A compression spring 72 coiled around the guiding pin tends to push the roller 69 towards the left-hand end of the slot 73. The roller 69 is guided by glide-discs 74 along the walls of the rocking arm and of the cover sheet 77. At one end of the roller an actuating knob 78 is provided, and at the other end there is an abutment disc 79.

The front and rear cover plates 60 and 66 are provided with cam guides 78 (FIG. 12) extending in an upward and outward direction from below and terminating at the top in a notch 63.

Upon the rocking arms being rocked out of the downwardly directed transport position illustrated in FIG. 12 for the right-hand rocking arm, the associated roller 69 glides upwards along the cam guides 78 while it moves within the slot 73 towards the outer end of the rocking arm, overcoming the thrust of the compression spring 72, until the detent roller snaps into the notch 63. In this position the upper edge of the associated rocking arm 68 abuts against an inclined surface 64 in the slot 59.

The lower rocking-arm ring 92 carries the lower rocking arms 95 rockably about pivots 94 on a rocking-arm bearing 93.

As the lower rocking arms rock upwards, they penetrate, in the vicinity of the rocking pivots, into slots 96, which are provided in guiding blocks 97 on the two outer sides of the rocking-arm bearing 93, until they come into contact with the base 98 of these slots 96. The rocking arms 95 are thereby secured against tilting, and at the same time the pivots 94 are relieved.

The lower rocking arms are likewise channel-shaped and shallow, but are so much narrower in breadth than the rocking arms 68 that, when both pairs of rocking arms are folded down, the lower portions of the upper rocking arms 68 embrace the lower rocking arms 95, as shown in

FIG. 11. A particularly compact formation in the transport position is thereby attained.

The two pairs of rocking arms are held in the transport position by means of a resilient locking band 99 wound around them and attached to a latch 100.

The mounting and demounting and the construction of the feet 101 of the stand shown in FIGS. 8-14 are the same as in the first embodiment. The feet of the stand are also held in the same manner, between the lower rocking-arm ring 92 and the clamping-ring 102, for the transport position. The only difference is that in the present embodiment the clamping ring 102 is arranged underneath the lower rocking-arm ring, whereas in the first embodiment the clamping ring is supported above the lower

rocking-arm ring.

In the embodiment illustrated in FIGS. 15 and 16, at the ends 104, 109 of the rocking bars 6, 7 or 25, 26 instead of the pins 47, as shown in the embodiment illustrated in FIGURES 1 and 2, generally rectangular 20 shackles 106, 111, rotatable about rivets 105, 110, are provided. On the sides of the shackles orthogonal to the rocking bars these shackles have pins 107, 112, each of which is connected with a corresponding bore or recess in the battens 108, 113 of the flexible projection screen, 25 thus serving for the bearing and stretching of the flexible projection screen.

In accordance with the construction shown in FIGS. 17 and 18, in departure from the showing in FIG. 1 the base 29 shown there is replaced by base 115 of a rectangular shape which is pushed from below over the lower tube member 114 by means of its socket 121 and fixed thereto. The base 115 carries in bearing holes 122 bolts 116 which are flattened in the respective ends 117 protruding from the base and are provided with a transverse bore 118 through which a pivot 119 extends for the pivotal mounting of the respective feet 120.

In the position of use each foot 120 rests with an upper lug 121 against the base 115 so that the stand rests on the floor at the ends 123 of the four feet only. For transport purposes each foot is rotated around its longitudinal axis whereby the second pivot means 116 in the bearing hole 122 is rotated until the lug 121 extends vertically downwardly. Then the foot member 120 can be tilted around the pins 119 forming the first pivot means towards the tube member 114 as this is illustrated on the left in FIG. 17 regarding one foot member.

What I claim is:

1. In a collapsible stand for a projection screen, in combination, a base; an upright post mounted on said base; an upper and a lower carrier member secured to said post at an upper location close to its top and at a lower location remote from said top, respectively; a pair of rigid first arms pivotally connected with said upper carrier member for swinging displacement substantially in a plane parallel to said post outwardly into an operative position, wherein said first arms diverge upwardly beyond said post, from an inoperative position wherein said first arms extend substantially codirectionally with said post; a pair of rigid second arms pivotally connected with said lower carrier member for swinging displacement substantially in said plane outwardly into a downwardly diverging operative position from an in-operative position wherein said second arms extend substantially codirectionally with said post; a projection on the free end of said first and second arms engageable with an upper and a lower batten, respectively, of a projection screen; latch means at each of said free ends for releasably maintaining the battens so engaged in positively connected relationship with said arms; holding means on each of said members for retaining the respective arms in their operative positions, at least one of said members being longitudinally shiftable on said post; and tightening means on said post operatively connected with said one of said members for relatively displacing said members longitudinally away from each other, thereby tensioning

the projection screen spanning said battens in the operative positions of said arms.

2. The combination according to claim 1 wherein the holding means of each of said members includes respective fixed abutments engageable with the respective arms in the operative positions thereof.

3. The combination according to claim 1 wherein said base is provided with a central portion, a plurality of feet, first pivot means connecting said feet with said central portion for swinging movement about axes transverse to said feet from operative positions wherein said feet extend generally radially to inoperative positions wherein said feet extend generally in a common direction and second pivot means having respective radial axes interconnecting each of said feet with said central portion whereby said feet can be swung about their respective radial axes to lock them in their operative positions.

4. The combination according to claim 1 wherein said latch means on the free end of each of said arms comprises a generally J-shaped shackle positionable to embrace the respective batten.

5. The combination according to claim 1 wherein the arms of at least one of said pairs are channeled to receive the arms of the other of said pairs in the inoperative positions of said arms, said arms of said one of said pairs overlying the arms of said other of said pairs in said inoperative positions.

6. The combination according to claim 1 wherein said post is tubular and adapted to receive said screen in a rolled-up condition thereof, further comprising removable cover means at the upper end of said post for closing the interior thereof.

7. The combination according to claim 6 wherein said post comprises a pair of telescopic sections, each of said members being mounted upon a respective one of said sections.

8. In a collapsible stand for a projection screen, in combination, a base; an upright post mounted on said base; an upper and a lower carrier member axially spaced along said post; a pair of first arms pivotally connected with said upper carrier member for swinging displacement substantially in a plane parallel to said post outwardly into an operative position wherein said first arms are detachably engageable with an upper batten of a projection screen at locations spaced on opposite sides

of said post from an inoperative position wherein said first arms extend substantially codirectionally with said post; a pair of second arms pivotally connected with said lower carrier member for swinging displacement substantially in said plane outwardly into an operative position wherein said second arms are detachably engageable with a lower batten of a projection screen at locations spaced on opposite sides of said post from an inoperative position wherein said second arms extend substantially codirectionally with said post; holding means on each of said members for retaining the respective arms in their operative positions, at least one of said members being longitudinally shiftable on said post; tightening means on said post operatively connected with said one of said members for relatively displacing said members longitudinally away from each other, thereby tensioning a screen spanning said battens in the operative positions of said arms, said base being provided with a central portion and a plurality of angularly spaced radially extending feet removably secured to said central portion; and retaining means on said post for holding said feet thereagainst upon their removal from said central portion, one of said members being provided with a plurality of angularly spaced recesses, said feet each being provided with a first extremity receivable in a respective one of said recesses, said retaining means including a ring independent of said one of said members and longitudinally shiftable on said post into engagement with other extremities of said feet for holding same against said post.

9. The combination according to claim 8 wherein said first extremities of said feet are each formed with resilient portions yieldably engageable with complementary formations provided in said central portion of said base.
